UNITED STATES PATENT OFFICE.

WILLIAM JOHN BERNARD TERRY, OF LONDON, ENGLAND, ASSIGNOR TO EISENMANNS
& CO., OF LONDON, ENGLAND.

DESIGN FOR A TOY.

43,858.

Specification for Design.

Patented Apr. 15, 1913.

Application filed January 18, 1913. Serial No. 742,954. Term of patent 3½ years.

To all whom it may concern:

Be it known that I, WILLIAM JOHN BERNARD TERRY, a subject of the King of Great Britain, residing at London, England, have invented a new, original, and ornamental Design for a Toy, of which the following is a specification, reference being made to the accompanying drawing, forming part thereof.

The figure is a perspective view of a toy showing my new design.

I claim:

The ornamental design for a toy, as shown.

WILLIAM JOHN BERNARD TERRY.

Witnesses:

R. WESTACOTT,
ALFRED MYERS.
